UNITED STATES PATENT OFFICE.

LINUS J. McADAM, OF BARKER, NEW YORK.

CARBURETER.

1,155,829.

Specification of Letters Patent.

Patented Oct. 5, 1915.

Application filed March 21, 1914. Serial No. 826,223.

To all whom it may concern:

Be it known that I, LINUS J. McADAM, a citizen of the United States, residing at Barker, in the county of Niagara and State 5 of New York, have invented a new and useful Improvement in Carbureters, of which the following is a specification.

This invention relates to carbureters for internal combustion engines and has for its 10 primary object to produce an efficient and practical carbureter by means of which low grade fuels, such, for example, as kerosene, which are less volatile than gasolene, can be successfully and economically used in the 15 operation of internal combustion engines.

Other objects will appear from the following description.

According to this invention the liquid fuel is first atomized, preferably by means of 20 compressed air, and an initial mixture of fuel and air produced in which the fuel is only atomized or partially vaporized, and this initial mixture is caused to commingle, preferably at successive points on its way 25 to the engine, with additional supplies of air under pressure and atmospheric air whereby the atomized or partially vaporized fuel is thoroughly vaporized and mixed with the necessary volume of air to produce an 30 explosive mixture suitable for use in internal combustion engines.

In the accompanying drawings, Figure 1 is a diagrammatic elevation, partly in section, showing a carbureter embodying the 35 invention. Fig. 2 is a fragmentary sectional elevation, enlarged, of the atomizing device. Fig. 2^a is a section on line x—x, Fig. 2. Fig. 3 is an enlarged side elevation of the carbureter. Fig. 4 is an end elevation thereof. 40 Fig. 5 is a sectional elevation, enlarged, of the atomizing nozzle and connected chamber. Fig. 6 is an enlarged longitudinal sectional elevation of the carbureter, showing the throttle valve closed. Fig. 7 is a similar 45 view showing the throttle valve partially opened. Fig. 8 is a similar view of the throttle and air regulating valves, showing them both opened. Fig. 9 is a sectional elevation in line 9—9, Fig. 8.

50 Like reference characters refer to like parts in the several figures.

A, Fig. 1, represents an internal combustion engine, B a tank or reservoir containing the liquid fuel, and C a reservoir for 55 compressed air which is supplied by any suitable means, such as a compressor D

driven by the engine, and connected by a pipe d to the air reservoir C, in which the pressure is preferably maintained substantially constant by pressure controlling means (not shown) such as commonly employed for this purpose in motor driven vehicles. Air is preferably supplied from the air reservoir C to the fuel tank to maintain pressure therein by a pipe e.

F represents one or more fuel supply pipes which lead from the lower portion of the fuel tank B to a fuel atomizing nozzle G, and H represents a pipe for supplying compressed air to the nozzle for atomizing the 70 fuel. In the construction shown, the atomizing nozzle is connected to one end of the air supply pipe H which is connected at its other end to and communicates with the upper portion of the fuel tank B, and there 75 are two of the fuel supply pipes F of small gage which pass through and are inclosed by the air pipe H as shown in Fig. 2^a. The atomizing nozzle G discharges the atomized fuel into an initial mixing pipe or chamber 80 I to which the nozzle is connected in any suitable manner. The fuel is discharged into this pipe I by the pressure of the air on the fuel in the fuel tank B and by the flow of compressed air through the pipe H, and is atomized and mixed with the air in the pipe I, which is preferably provided with an enlargement or casing i at the nozzle end thereof of sufficient size to permit the proper expansion and mixture of air and 85 atomized fuel.

The air supply pipe H is provided at an appropriate point with an air inlet valve h of any suitable sort adapted to be opened by the suction or vacuum created by the engine to admit atmospheric air to the pipe H. This valve also serves to admit air to the fuel tank and prevent the formation of a sufficient vacuum therein to interfere with the proper operation of the carbureter or 95 the possible collapse of the fuel tank.

The initial mixing pipe or chamber I connects, preferably at an acute angle, with a supplemental mixing pipe or chamber K to which a supplemental supply of compressed air is conducted from the air reservoir C by a pipe L which preferably connects with the mixing pipe or chamber K at an acute angle in rear of the connection of the pipe I therewith. This supplemental mixing pipe or chamber K connects with the intake manifold of the engine A through 105 110

suitable connections controlled by a throttle valve hereinafter described.

M represents an auxiliary air admission valve which is connected with the supplemental mixing pipe or chamber K and is opened automatically by the suction of the engine to admit atmospheric air to the supplemental mixing pipe or chamber. As shown, this auxiliary air admission valve 10 comprises a casing m connected to the pipe K and having a conical end provided with air inlet openings m', and a bell m² which is arranged to slide on a tube m³ in the casing m and has a large open end opposite the mixing pipe or chamber K and a closed conical end adapted to close the inlet openings m' in the conical end of the casing. The tube m³ is provided with entrance holes m⁴ adapted to be covered by a sleeve m⁵ attached to the bell, and exit holes m⁶. When the engine creates a partial vacuum or suction in the supplemental mixing pipe or chamber K the bell will be drawn inwardly, as indicated in Fig. 7, and the air will pass 25 through the inlet openings m' and the holes m⁴ and m⁶ in the tube m³ into the supplemental mixing pipe or chamber. The bell will be moved outwardly by pressure in the supplemental mixing pipe or chamber K and will close the entrance holes m⁴ in the tube m³ and thus cut off the admission of air or the escape of compressed air when the engine is not in motion. A valve of any other suitable construction adapted to control the 30 admission of air in accordance with the demands of the engine could be used in place of the valve M described.

The in-rushing columns of compressed air from the pipe L and atmospheric air admitted by the valve M meeting the preliminary mixture of atomized fuel and air from the preliminary mixing chamber I act to further subdivide or break up the atomized or partially vaporized fuel and to thoroughly vaporize and intimately mix the same with the additional volume of air in the supplemental mixing pipe or chamber and produce an explosive mixture which will 45 ignite readily in the engine at ordinary atmospheric temperatures, thus permitting the engine to be started without heating the explosive charge even in cold weather.

By atomizing and vaporizing the fuel by means of compressed air in the manner explained, the vaporization is so complete that it is not necessary for the engine to be warm or driven at high speed in order to properly vaporize the fuel as in the case of carbureters in which the vaporization is due to the 50 suction produced by the engine, and the described construction therefore enables the engine to be readily started even when cold, with such low grade fuels as kerosene. The compressed air supplied by the pipes H and 55 L gives a mixture suitable for starting, and

when the engine is in operation the automatically opening air valves h and M supply the necessary additional air for ordinary running conditions.

N represents the throttle valve of the carburetor. This valve preferably comprises a funnel-like casing n having a central open-ended sleeve n' extending through it, in which slides an open-ended tubular valve n² adapted to open and close tapering ports n³ in the sleeve n'. The supplemental mixing pipe or chamber K connects with the large end of the valve casing n at one side of the sleeve n', and the sleeve is connected at the small end of the casing with an outlet pipe O leading to the intake manifold of the engine so that the explosive mixture must pass from the supplemental mixing pipe or chamber through the casing n and the ports n³ in the sleeve n' controlled by the valve n². The valve n² can be actuated to control the passage of the explosive mixture to the engine by any suitable means. A lever P, fulcrumed on a bracket p secured to the valve casing and connected to a yoke p' attached to the valve, is shown for this purpose. p² is an operating rod attached to the lever and adapted to extend to any convenient point for operation.

Q represents an air regulating and safety valve which normally closes the outer end of the throttle valve n² but is adapted to be opened to admit air for increasing the proportion of air in the explosive mixture when the running conditions admit of the use of a leaner mixture. The valve Q shown consists of a plug slidable in the outer end of the tubular throttle valve n² and having tapering peripheral slots q which provide passages through which the air is admitted when the air valve is pulled outwardly or opened. The valve is closed by a spring q' and also by the suction or aspiration of the pistons. The means shown for opening the valve consist of a lever q² pivoted on the bracket p and engaging an adjustable nut on the valve stem q³, and an actuating connection leading to a convenient point for operation. The air valve can, however, be operated by any other suitable means, either manual or automatic. This valve is adapted to be opened against the action of its closing spring by pressure on its inner end, and it therefore acts as a safety valve in the case of a back-fire, affording an opening to the atmosphere for the burning gases.

R and S indicate valves in the compressed air pipes e and L for shutting off the compressed air when the carburetor is not in use. These valves can be operated simultaneously by any suitable means, such as arms r and s on the valves connected by a rod t and attached to an operating rod t'. These valves, R and S, could be dispensed with if the

throttle valve were arranged to close tightly, but it is desirable to have the throttle valve arranged so that when closed it will leave the usual slight passage for the mixture in order to prevent stalling the engine when closing the throttle valve to slow down the engine. The valves R and S are therefore preferably used for shutting off the compressed air in order to prevent the formation of an explosive mixture in the supply tube beyond the throttle valve when the throttle valve is slightly open.

I claim as my invention:

1. In a carbureter, the combination of a fuel atomizing device, a tube having an opening in its side into which the atomized fuel is admitted, an air inlet valve at the end of said tube, and means for admitting compressed air into said tube in proximity to the inlet for said atomized fuel.

2. In a carbureter, the combination of a fuel atomizing device, a tube into which the atomized fuel is admitted, an air valve for admitting air into said tube, said valve having a member which is moved in one direction by the suction within said pipe to open the valve and which is moved in the opposite direction by compression to close the valve, and means for admitting compressed air into said tube.

3. In a carbureter, the combination of a mixing chamber connected with the intake of an internal combustion engine, means for atomizing liquid fuel, a pipe into which said atomized fuel is discharged and which connects with said mixing chamber, and a pipe connecting a source of air under pressure with said mixing chamber in rear of the connection of said atomized fuel pipe therewith, and means under the control of the engine for admitting additional air to said mixing chamber in rear of the connection of said atomized fuel pipe therewith.

4. In a carbureter, the combination of a fuel atomizing device, a pipe for supplying air under pressure to said atomizing device to atomize the fuel, a passage which is connected with the intake of an internal combustion engine and into which said atomized

fuel is discharged, suction-operated valves for separately admitting atmospheric air to said compressed air supply pipe and to said passage, and means for delivering a supplemental supply of compressed air to said passage adjacent to the portion thereof into which the atomized fuel is admitted.

5. In a carbureter, the combination of a fuel atomizing device, a tube into which the atomized fuel is admitted, an air valve for admitting air into said tube, said valve having a member which is moved in one direction by the suction within said pipe to open the valve and which is moved in the opposite direction by compression to close the valve, means for admitting compressed air into said tube, and a safety valve adapted to be opened by abnormal pressure.

6. In a carbureter, the combination of a fuel atomizing device, means for supplying air under pressure to said atomizing device to atomize the fuel, a passage which is connected with the intake of an internal combustion engine and into which said atomized fuel is discharged, means for supplying additional air to said passage, a throttle valve controlling said passage, and a safety valve adapted to be opened by abnormal pressure in the casing of said throttle valve.

7. In a carbureter, the combination of a fuel atomizing device, means for supplying air under pressure to said atomizing device to atomize the fuel, a passage which is connected with the intake of an internal combustion engine and into which said atomized fuel is discharged, means for supplying additional air to said passage, a tubular throttle valve controlling said passage, and a safety valve which normally closes the passage through said tubular throttle valve and is adapted to be opened by abnormal pressure in said throttle valve.

Witness my hand, this 16th day of March, 1914.
